UNITED STATES PATENT OFFICE.

HENRY D. HUGHES, OF RADNOR, AND EDWARD SHALLOW, OF PHILADELPHIA, PENNSYLVANIA.

HYDROCARBON-BURNER.

SPECIFICATION forming part of Letters Patent No. 364,931, dated June 14, 1887.

Application filed December 15, 1886. Serial No. 221,686. (No model.)

To all whom it may concern:

Be it known that we, HENRY D. HUGHES and EDWARD SHALLOW, citizens of the United States, the said HENRY D. HUGHES residing at Radnor, Delaware county, Pennsylvania, and the said EDWARD SHALLOW residing at Philadelphia, in the county of Philadelphia and State of Pennsylvania, have invented a certain new and useful Improvement in Hydrocarbon-Burners; and we do hereby declare the following to be a full, clear, and exact description of the invention, such as will enable others skilled in the art to which it appertains to make and use the same.

15 Our invention relates to burners for consuming hydrocarbon oils in which the oil is atomized or vaporized by means of a jet of steam or air made to pass immediately in front of the nozzle or discharge-tip of the oil-tube.
20 The objects of our improvement are, first, to avoid the constant dripping of oil from the burner-tip, so common in burners of this kind when constructed in the ordinary manner; second, to more thoroughly and easily 25 vaporize the oil and at the same time mingle therewith a sufficient quantity of air or steam, or both, so as to bring about a perfect combustion; third, to easily and correctly adjust the relative positions of the burner-tip and the 30 discharge-nozzle for the steam or air; fourth, to supply the burner with such a quantity of heated air that the pressure of the steam may be very materially reduced and the loud noise made by the rushing steam in a great measure 35 avoided.

In the accompanying drawings, Figure 1 is a side elevation of our improved burner. Fig. 2 is an end elevation. Figs. 3 and 4 are vertical sections of the nozzle or burner-tip, showing the construction thereof and the manner 40 of connecting to the other parts of the device. Fig. 5 is a section of a lime-kiln or other structure having one of our burners attached.

A is an oil-tube communicating with the 45 oil-reservoir, which is located some distance away and below the level of the outlet to the burner.

A' is the head of the burner, secured vertically on the oil-tube at right angles thereto.
50 " is a nut or bushing screwed into the head A'.

a' is a small tube fitting into the bushing a, and surrounded with a packing, a'.

a' is a triangular slot in the tube a'.

a' is an arm fastened to the tube a', and carrying the end of the thumb-screw a'. This 55 thumb-screw has a bearing, b, secured on the head A'.

b' is the outlet-nozzle or burner-tip screwed into the lower end of the tube a'. The rear end or inlet-orifice of this burner-tip b' is circular in shape, while the outlet or discharge opening is flat, as shown in the drawings.

B is a steam-pipe, connected with any convenient steam-generator.

C is a contracted nozzle screwed into the 65 ends of the pipes B and D. This nozzle is securely held in place by means of the jam-nut n.

E is a hot-air tube secured to the tube D, and connected with a heated coil or any other convenient means for heating the air before it 70 passes into the pipe D. The nozzle C of the steam-pipe B is extended into the tube D a short distance beyond the point where the hot-air inlet C is connected. (See Fig. 1.)

e is a bushing secured in the forward end 75 of the tube D.

e' is a small tube fitting into the bushing e, and surrounded by a suitable packing to secure a tight joint. The tube e' is similar in construction to the tube a'; but it does not have 80 the triangular slot therein.

c' is an extending arm on the tube e', and carrying the thumb-screw c'. This thumb-screw has a stationary bearing, d, secured to the body of the burner.

d' is the outlet nozzle or discharge-tip for the hot air and steam. This nozzle or tip is identical in construction with the oil-nozzle b' on the end of the oil-tube, and has a circular inlet and a flat outlet.

The position of the oil-nozzle b' is adjusted up or down by means of the thumb-screw a', and the nozzle d' is moved back or forward by means of the screw c'. Thus a nice adjustment is obtained and the nozzles can readily and 95 easily be put into the most advantageous positions. The tube a' being provided with the triangular slot a', the supply of oil can be increased or diminished by simply screwing the tube a' up or down. The inlet-orifice of the 100

oil-nozzle *b'* being circular and the outlet flat, when the oil is drawn through the natural cohesion of the particles is thereby broken up, allowing the current of air or steam to more readily act upon it and reduce it to a vapor as it is discharged at the outer tip of the burner. The steam and air entering the tube *D* at different points the supply of each is easily regulated, and when both are used together they are thoroughly commingled in the pipe *D* before being discharged through the outlet-nozzle. If the steam is too damp, it is brought to a sufficient degree of dryness by increasing the flow of hot air. Consequently a very low pressure of steam may many times be maintained. As the head of the burner *A'* is at right angles to the horizontal oil-supply tube, the burner-tip is in a vertical position and always placed over the nozzle of the discharge-orifice for the steam and air. This arrangement completely overcomes the natural tendency of the oil to liquefy and drip down off the burner-tip.

The burner being constructed and arranged as herein shown, the tube *A* is connected with an oil-tank located below the level of the burner, the steam-pipe *B* is connected with a steam-boiler, and the hot-air tube connected with a heated coil of pipe located at any convenient point. When desiring to use the burner, the steam is turned on through the pipe *B*, when it will be forced through the nozzle *C* into the pipe *D*, creating a vacuum therein, and causing the heated air to rush in through the pipe *E* and mix with the escaping steam, when the commingled air and steam are discharged from the flat opening of the discharge-tip *d'* immediately below and in front of the nozzle or tip on the end of the oil-tube, and by this means drawing or sucking the oil from the reservoir through the tube *A* into the tube *a'*, passing from thence into the burner-tip *b'*, being discharged therefrom through the flat orifice, when it is immediately converted into a vapor, commingling with the air and steam discharging from the nozzle *d'*. In this condition it is ignited and will readily burn.

We are aware that injector-burners have heretofore been made with oil-tubes having adjustable flat tips, and that steam and hot-air tubes discharging through a single flat orifice, which is adjustable, have been known, and we do not claim such, as our invention differs therefrom in the particulars which are specified in the following claims.

Having thus described our invention, what we claim as new, and desire to secure by Letters Patent of the United States, is—

1. The combination, with the oil-pipe *A*, having a head, *A'*, set at right angles thereto on one end thereof, a movable tip having a tube or extension projecting into the head *A'* and free to move therein, and a screw for adjusting said tip and extension in said head, of the tube *D*, having the steam and hot-air pipes connected and discharging into it, a tip having a tube extending movably into tube *D*, and a screw for adjusting the same, substantially as set forth.

2. In a burner of the kind described, the combination, with the oil-tube *A*, having the head *A'*, of the tube *a'* and tip *b'*, said tube having the slits or openings *a'* cut down from the upper end thereof, and an adjusting-screw for moving said tube *a'*, and the air and steam pipes having a single discharge-orifice adjustable therein, as set forth.

3. The combination, with the oil-pipe or tube *A*, having head *A'* and an adjustable tip therein, of the tube *D*, having the steam and hot-air pipes both discharging into it, the adjustable bushing *c*, screwed into the end of tube *D*, and the movable tube *a'*, having tip *d'* projecting into bushing *c*, and screw for adjusting the same, substantially as set forth.

In testimony whereof we affix our signatures in presence of two witnesses.

HENRY D. HUGHES.
EDWARD SHALLOW.
